UNITED STATES PATENT OFFICE.

DAVID FRANCIS CRAWFORD, OF PITTSBURG, PENNSYLVANIA.

MECHANICAL STOKER FOR LOCOMOTIVES.

941,698.

Specification of Letters Patent. Patented Nov. 30, 1909.

Application filed October 3, 1908. Serial No. 456,087.

To all whom it may concern:

Be it known that I, DAVID F. CRAWFORD, a citizen of the United States, residing at Pittsburgh, in the county of Allegheny and State of Pennsylvania, have invented certain new and useful Improvements in Mechanical Stokers for Locomotives, of which the following is a specification.

The invention relates to stoking mechanism of the under-feed type for locomotives, and has for its principal objects: the provision of an improved feed mechanism which may be applied to the majority of locomotives as now constructed and without interference with or change in the other structural features of the locomotives; and the provision of improved means for securing proper upward feed from the trough. Certain embodiments of the invention are illustrated in the accompanying drawings, wherein:—

Figure 1 is a central longitudinal section through the fire box and stoker,

Figure 2 is a partial end elevation and partial section on the line II—II of Figure 1, and shows the operating mechanism for the feeding device at the end of the fire-box, and

Figure 3 is a partial longitudinal section similar to that of Figure 1, but showing a slightly modified form of trough construction.

The general construction of the furnace follows that shown and described in my co-pending application, Serial No. 387,297, but differs therefrom in the mechanism for securing the feed to the trough and in the construction of the trough itself. Only so much of the fire-box and other locomotive parts is shown as is necessary to indicate the location of the stoker and its operating mechanism.

Referring to the drawings, 1 is the firebox of the locomotive, 2 is the feed trough extending along the center of the furnace, 3 is one of the side grates, similar in construction to that shown and described in detail in my co-pending application referred to, and 4 is a drop grate extending transversely 50 across the front end of the furnace.

One of the features of my invention resides in the mechanism for feeding the coal to the trough 2, and this mechanism will now be described in detail. By reference to Figures 1 and 2, it will be noted that a hopper 5 is provided at the front end of the fur-

nace, which hopper leads to a feed cylinder or passage 6, such feed passage being in alignment with the end of the trough 2. The fuel for the furnace is introduced into the hopper 5 and is fed step-by-step through the passage 6 by means of a reciprocatory feed member 7 slidably mounted in the feed passage. The feed member 7 is provided with a transversely extending shaft 8, which shaft carries a cross head 9 mounted in the slots 10 at the sides of the passageway 6. The sides of the cylinder 6 are provided with the rearwardly extending guide members 22 lying above the usual coupler head 23. The source of motive power for reciprocating the feed member 7 is the steam cylinder 11 mounted at the side of the fire-box as indicated in Figures 1 and 2. The piston of this cylinder carries pivoted thereto a rod 12, which rod is pivoted at its outer end to a crank 13 keyed to the shaft 14. This shaft extends transversely across the front of the fire-box and carries the cranks 15—15, which cranks are connected to the shaft 8 carried by the feed member 7 by means of the links 16. The fuel in the trough 2 is agitated to promote its upward feeding by means of a member 17 mounted upon the reciprocating rod 18, which rod 18 is moved from the shaft 14 by means of a crank 19 and connecting link 20. The agitating member 17 may be placed at any desired point along the rod 18. As indicated in Figure 1, the bottom of the trough 2 is provided with a hump 21. The purpose of this hump or projection is to loosen the mass of material in the trough and promote an upward feed so that a sufficient body of coal will be spread laterally over the side grate at this portion of the furnace. The number and location of the humps may be varied to suit conditions.

It will be seen from the foregoing description of the operating mechanism that very little space adjacent the front of the fire-box is occupied by such mechanism, and that the device may be applied readily to the standard type of locomotive. The cylinder 11 is readily accessible at the side of the fire-box and plenty of space is available at this point without interference with other of the locomotive parts. Furthermore, by this arrangement plenty of clearance is available in the cab immediately behind the feeding mechanism, which clearance is absolutely necessary in nearly all locomotives of stand-

ard construction. One advantage in shortening the cylinder 6 and employing the rearwardly extending guide members 22, is that the coupler head 23 is made accessible 5 from above and the pin employed may be readily removed between the members 22. The cross head 9 prevents any twisting of the feed member 7 and permits such member to be made shorter than would be the case if 10 no guiding cross head were employed.

The construction shown in Figure 3 is the same as that of Figures 1 and 2 with the exception that the hump in the bottom of the feed trough is omitted and a member 17' is 15 substituted therefor, which member is secured to the rod 18'.

Having thus described my invention and illustrated its use, what I claim as new and desire to secure by Letters Patent is the following:

1. The combination of a locomotive furnace, an under-feed trough extending into the furnace, a feed cylinder located at the rear of the trough and provided in its sides 23 with guide slots, guide members extending rearwardly from the opposite sides of the cylinder and provided with slots forming continuations of the first guide slots, a feed piston in the cylinder, a cross-head secured 30 to the piston fitting the guide slots, crank arms secured to the cross-head on opposite sides of the cylinder, and means for oscillating the crank arms.

2. The combination of a locomotive fur-

nace, an under-feed trough extending into 35 the furnace, a feed cylinder located at the rear of the trough and provided in its sides with guide slots, a feed piston in the cylinder, a cross-head secured to the rear portion of the piston and extending through the 40 slots, a transverse shaft provided with crank arms on opposite sides of the cylinder with their upper ends in front of the cross-head, connecting links extending from the cross-head to the ends of the cranks, an operating 45 crank arm located adjacent the end of the transverse shaft and a motor connected to such last crank arm for oscillating it.

3. The combination of a locomotive furnace, an under-feed trough extending into 50 the furnace, a feed cylinder located at the rear of the trough and provided in its sides with guide slots, a piston mounted in the cylinder, a cross-head fitting the slots, a transverse shaft beneath the cylinder, an 55 operating motor located at the side of the fire-box and having connections with the shaft for oscillating it, and a crank at the side of the cylinder and having operative connection with the cross-head and with the shaft.

In testimony whereof I have hereunto signed my name in the presence of the two subscribed witnesses.

DAVID FRANCIS CRAWFORD.
